ABSTRACT OF THE DISCLOSURE

An expansion compensator connecting a heater element and a current-carrying terminal of a high temperature heater such as in high pressure furnaces in which the temperature may reach as high as 3200° C. and the pressure as high as hundreds of atmospheres. The compensator is an axially deformable graphite body in the form of a sylphon, spiral spring, zig zag member, or the like.

The present invention relates to electrothermal equipment, and more particularly to an expansion compensator for high temperature electrothermal heaters, preferably in high-pressure and vacuum electric furnaces.

There are known expansion compensators formed as simple elastic members that are not to be cooled and are suitable for temperatures up to 1400° C. The extensively used compensators of the type of metal sylphon and water-cooled pipe spring cannot be employed in the high-pressure electric furnaces, because an increase in the pressure of gas in the furnace must be matched with an increase in the thickness of the compensator walls (both the sylphon and pipe), and consequently in the compensator rigidity. The latter is likely to annul the compensating capacity of the compensator.

An object of the present invention is to provide a simple and reliable design of the expansion compensator for high temperature heaters of electrothermal devices.

According to the present invention, this object is accomplished by a compensator made of graphite. The compensator may be in the form of a zigzag, a sylphon, or a spiral spring.

A more complete understanding of the invention may be had by reference to the accompanying drawings, in which:

FIG. 1 is a cross-sectional view of a zigzag expansion compensator, the associated apparatus being shown in phantom;

FIG. 2 is a cross-sectional view of two zigzag expansion compensators, the associated apparatus being shown in phantom (two compensators assembled by means of a connecting bus bar);

FIG. 3 is a general cross-sectional view of a zigzag duplex expansion compensator, the associated apparatus being shown in phantom;

FIG. 4 shows an expansion compensator, partly broken away, in the form of a sylphon, the associated apparatus being shown in phantom;

FIGS. 5 and 6 show expansion compensators in the form of spiral (cylindrical and conical) springs, the associated apparatus being shown in phantom.

As follows from a consideration of FIGS. 1, 2 and 3, a zigzag compensator 1, having several elastic members in the form of brackets 2, is connected to a heater 3 by means of a non-cooled contact 4 and a nut 5, and to the current-carrying busbar 6 by means of bolts 7.

The expansion compensator, in the form of sylphon 8 (FIG. 4), is provided with a number of elastic members in the form of corrugations 9. A non-cooled contact 4 is employed to connect the compensator to the heater 3, while the current-carrying busbar 10 is screwed directly on the compensator housing.

The compensator 11, in the form of spiral springs (cy-

2

lindrical, FIG. 5; conical, FIG. 6), is provided with a plurality of elastic members in the form of coils 12. The non-cooled contact 4 is employed to connect the compensator to the heater 3, while the current-carrying busbar 10 is screwed directly onto the compensator housing.

The current-carrying or connecting busbar can unite two to three or even more heaters through a corresponding number of compensators.

The compensator operates as follows. When the electric current is passed through the heaters, the latter are heated to as high a temperature as 1800 to 3200° C. Each heater will have different heat expansion on account of a plurality of factors, such as various chemical compositions, density, length, diameter, etc. Therefore, to protect the heaters, each of them is provided with a graphite compensator of the construction indicated hereinabove which allows each heater to expand independently. The compensation is provided by the elastic deformation of zigzag bracket plates 2 (FIGS. 1, 2 and 3), and annular corrugations 9 of the sylphon 8 (FIG. 4), and coils 12 of the spring (FIGS. 5 and 6).

The described compensators of the thermal expansion of high temperature heaters are simple in design and easy to manufacture, operating in the temperature range from 1800 to 3200° C. practically at any ambient pressure. The ambient medium may be gas or a mixture of gases that do not react with graphite at the indicated temperatures; namely, hydrogen, hydrocarbons, ammonia, and inert gases.

Said compensators allow to design electrothermal vessels or compact furnaces with one or a plurality of heaters, which permits the construction of furnaces for high pressures, of the order of hundreds of atmospheres.

The magnitude of expansion to be compensated is controlled in two ways:

(a) By varying the number of brackets 2 (FIGS. 1, 2 and 3), annular corrugations 9 (FIG. 4), and coils 12 (FIGS. 5 and 6);

(b) Varying the length of brackets 2 (FIGS. 1, 2 and 3), the difference between the maximum and minimum diameters of the annular corrugations 9 (FIG. 4), and the ratio of the difference of diameters of the coil 12 to the height of said coil 12 (FIGS. 5 and 6).

The overall dimensions of the compensators depend on the value of the expansion to be compensated and the size of the heaters.

What is claimed is:

1. In a heater having a heater element and a current-carrying terminal, a compensator connecting said heater element and terminal, said compensator being constituted of graphite and being constructed to be axially deformable to thereby enable expansion of the heater element at temperatures as high as 3200° C. and at pressures of the order of hundreds of atmospheres.

2. The apparatus as claimed in claim 1 wherein said compensator is constituted by bracket plates in zigzag shape.

3. The apparatus as claimed in claim 1 wherein said compensator includes annular corrugations to provide a sylphon configuration.

4. The apparatus as claimed in claim 1 wherein said compensator includes a coil wound in the form of a spring.

5. The apparatus as claimed in claim 4 wherein said spring is cylindrical.

6. The apparatus as claimed in claim 4 wherein said spring is conical.

7. The apparatus as claimed in claim 1 wherein two heater elements are provided, a compensator being connected to each heater element such that the compensators are parallel and adjacent one another, said compensators being connected to the same current-carrying terminal.

8. The apparatus as claimed in claim 1 wherein two

3
heater elements are provided, said compensator including two axially deformable branches each connected to a respective heater element, and a common body connected to said branches and to the current-carrying terminal.
